UNITED STATES PATENT OFFICE

103,384

DESIGN FOR A POTATO SLICER

Samuel Bloomfield, Chicago, Ill.

Application November 3, 1936, Serial No. 65,682

Term of patent 3½ years

To all whom it may concern:

Be it known that I, Samuel Bloomfield, a citizen of the United States and a resident of Chicago, in the county of Cook and State of Illinois, have invented a new, original, and ornamental Design for a Potato Slicer, of which the following is a specification, reference being had to the accompanying drawing forming a part thereof, and in which:

Fig. 1 is a side elevational view of a potato slicer showing my new design;

Fig. 2 is a plan view of the same; and

Fig. 3 is a perspective view of the same shown on slightly smaller scale.

I claim:

The ornamental design for a potato slicer, as shown and described.

SAMUEL BLOOMFIELD.
